A. H. HANDLAN

LANTERN FRAME

Filed July 5 1922

Inventor —
Alexander H. Handlan
by Cook & McCaulay Mfg.

UNITED STATES PATENT OFFICE.

ALEXANDER H. HANDLAN, OF ST. LOUIS, MISSOURI.

LANTERN FRAME.

Application filed July 5, 1922. Serial No. 572,790.

To all whom it may concern:

Be it known that I, ALEXANDER H. HANDLAN, a citizen of the United States of America, a resident of the city of St. Louis, in the State of Missouri, have invented certain new and useful Improvements in Lantern Frames, of which the following is a full, clear, and exact description, reference being had to the accompanying drawings, forming 10 a part of this specification.

This invention relates to improvements in lantern frames, and particularly to a lantern frame having four vertical guard wires, the main object of the invention being 15 to provide simple and durable means whereby a pivotally mounted bail may be securely attached to said lantern frame.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which 25 come within the scope of the claims hereunto appended.

Fig. I is a side elevation, partly in section, 30 showing a lantern frame of the square type equipped with my improved bail-attaching means.

Fig. II is a section on line II-II of Fig. I.

Fig. III is a front elevation of the bail-attaching means shown in Fig. I, portions of 35 the associated guard wires and bail being shown.

In the drawing, A designates a lantern frame which is provided with the usual hood B. The hood B, as is well known, is usually hinged to the frame A and is provided with a catch for retaining same in a closed position, but as these attachments are quite common it 40 is not deemed necessary to show same in the drawing or describe them in the specification. The lantern frame A includes four vertical guard wires C and a plurality of horizontal guard wires D, E and F. As is shown in 45 Fig. II of the drawing, the horizontal guard wires D, E and F are formed with flat por-

tions, which gives a comparatively square shape to the lantern frame, whereby the lantern may be suspended in such position that several of the flat portions mentioned 55 rest against a flat surface, thus eliminating any tendency of said lantern to rock if it be mounted on a vehicle or other moving object, or readily attached to a bracket. It will also be noted by reference to Fig. II 60 that there are but four vertical guard wires, thus giving greater opportunity for the light to be emitted from the lantern, due to the absence of a great number of vertical guard wires, each of which will, of course, cast a 65 shadow.

The vertical guard wires C are not properly positioned to receive the bail G, and for this reason I employ a pair of bail-attaching members 1, each of which preferably comprises a section of wire provided with a loop 2 at its upper end embracing the horizontal guard wire D, a loop 3 at its lower end embracing the horizontal guard wire E and an eye 4 formed in the portion of said wire 70 intermediate of said guard wires D and E, which eye receives a looped end of the bail G. 75

The bail-attaching members 1 are firmly clinched to the guard wires D and E, so that they are very securely held in place, and as 80 the guard wires of the lantern frame are also clinched to each other, a very rigid construction is obtained, which will withstand the rough usage to which the lantern is subjected. 85

I claim:

1. A lantern frame provided with a plurality of vertical guard wires and a plurality of horizontal guard wires, a bail having looped ends, and means comprising 90 sections of wire, the end portions of which embrace a pair of horizontal guard wires intermediate of pairs of vertical guard wires for securing said bail to said lantern frame, said sections of wire being located 95 entirely above that portion of the lantern frame wherein the burner of the lantern is arranged and each of said sections of wire being provided with an eye which receives a looped end of said bail. 100

2. A lantern frame provided with four vertical guard wires located at the corners

of said frame, a plurality of horizontal guard wires secured to said vertical guard wires, a bail having looped ends, and means comprising sections of wire, the end portions 5 of which embrace a pair of horizontal guard wires intermediate of pairs of vertical guard wires for securing said bail to said lantern frame, said sections of wire being located entirely above that portion of the lantern frame wherein the burner of the lantern 10 is arranged and each of said sections of wire being provided with an eye which receives a looped end of said bail.

In testimony that I claim the foregoing I hereunto affix my signature.

ALEXANDER H. HANDLAN.
